Gustavo Hernandez
ATTORNEY

UNITED STATES PATENT OFFICE.

EUGENIO FERNANDEZ, OF VALPARAISO, CHILE.

OVEN.

Application filed November 26, 1927. Serial No. 235,821.

This invention relates to a new and useful device in the nature of a combination stove and oven, particularly adapted for heating and cooking purposes.

5 The object of the invention is to provide a combination stove and oven of novel construction and arrangement of parts, herein-after more fully described, claimed, and illustrated in the accompanying drawing, in 10 which:

Fig. 1 shows a perspective front elevational view of my improved combination stove and oven, certain exterior parts removed so as to more clearly show the interior construction 15 thereof.

Fig. 2 shows a vertical sectional view thereof.

Fig. 3 shows a detail perspective front elevational view of the fire box, as embodied in 20 my improved device, certain exterior parts being removed, so as to more clearly show the interior construction thereof.

Fig. 4 is a top plan view of the grate bars.

As here embodied my improved device 25 comprises briefly, a fire box 10, of box-like construction, supported by the upright members 11, or legs, attached at the corners of the said fire box and extended downwardly thereof. The lower oven 12, is of similar box-like 30 construction, and is of suitable size to engage or fit on top of the fire box 10, or may be built integral therewith or attached thereto. The top oven 13, is of similar box-like construction, and is of suitable size to engage or 35 fit on top of the lower oven 12, or may be built integral therewith or attached thereto.

The fire box 10, comprises plate members 40 14 and 15, attached, at or near the upper portion of the fire box 10, and extended horizontally inwardly therefrom, so as to provide a central opening. The rods 16 and 17, are supported by the plate members 14 and 15, respectively, and are positioned adjacent to the above-mentioned opening formed by 45 the plate members 14 and 15. A plurality of grate bars 18 and 19, are pivotally attached, at their upper extremities, to the rods 16 and 17. The grate bars 18 and 19 are alternately positioned on the rods 16 and 17, so as to interlock each other. The rods 20 and 21, are attached to the lower extremities of the grate bars 18 and 19. The operating rods 22 and 50 23, are pivotally attached intermediate to the rods 20 and 21, respectively, and are extended outwardly therefrom, through apertures formed in the sides of the fire box 10. The

operating rods 22 and 23, have attached at their extended extremities ring members 24 and 25, handles or the like, respectively, and are provided with a plurality of notches 26 and 27, respectively, adapted to engage the apertures formed in the sides of the fire box 10, as a means of holding the grate bars 18 and 19 in any desired position, as clearly shown in Fig. 2 of the accompanying drawing. The above described construction is such as will permit the said grate bars to support the coal to be burned, in a pile, adjacent to or below the lower oven 12, as may be desired, and which will permit the ashes from the said 70 coal to be shaken into the lower portion of the fire box 10. The door 28, is provided with a handle 29, and is hinged, or otherwise removably attached to the front portion of the fire box 10, as a means of removing the ashes 75 from the said fire box.

The lower oven 12, is provided with a front opening 30, and a removable bottom member 31, supported by the cross members 32, attached to the lower portion of the lower oven 12. The above described construction is such as will permit coal to be placed on the grate bars 18 and 19, when the removable bottom member 31, is removed, and which will permit cooking utensils containing food 80 to be cooked or baked, to be placed on the removable bottom member 31, or on the cross members 32.

The top oven 13, is provided with a front opening 33, so as to permit cooking utensils 90 containing food to be cooked or baked, to be placed on the bottom thereof.

The lower oven 12 and the top oven 13, are constructed so as to provide a space or chamber at the sides and top thereof, and has positioned therein, intermediate the said ovens 12 and 13, baffle plates 34 and 35, extending horizontally, so as to provide a central opening. The chimney 36 is attached to the upper portion of the top oven 13, and is provided 100 with the usual damper 37, pivotally mounted therein, as a means of regulating the draft.

The plate members 14 and 15, are provided with elongated apertures 40 and 41, respectively, adapted to receive the threaded members 42, bolts, screws, or the like. The threaded members 42, are also positioned in apertures formed in the supporting members 43 and 44, attached to the fire box 10. The above-described construction is such as will 105 permit the above-mentioned plate members 14 and 15 to be increased or decreased, as may

be desired, as a means of varying the effectiveness of the fire on the grate bars 18 and 19.

Having thus described my invention, what I claim as new and desire to protect by Letters Patent of the United States is as follows:

1. In combination with an oven of the class described, plate members horizontally extended from opposite inner sides of the oven, 10 and forming an opening between the edges thereof, rods rotatively mounted on the plate members near the edges forming the said opening, grate bars pivotally attached at one of their extremities to the said rods, and directed towards each other and alternately positioned, other rods attached to the free ends 15 of the grate bars, and rods formed with a plurality of notches, attached to the said second mentioned rods, and adapted for extending thru apertures in the sides of the said oven, and arranged for permitting the said notches to engage the edges of the apertures for holding the rods in various extended positions, so as to hold the grate bars in various 20 inclined positions.

25

2. In combination with an oven of the class described, plate members horizontally extended from opposite inner sides of the oven, and forming an opening between the edges thereof, rods rotatively mounted on the 30 plate members near the edges forming the said opening, grate bars pivotally attached at one of their extremities to the said rods, and directed towards each other and alternately positioned, other rods attached to the free 35 ends of the grate bars, and rods formed with a plurality of notches, attached to the said second mentioned rods, and adapted for extending thru apertures in the sides of the said oven, and arranged for permitting the said 40 notches to engage the edges of the apertures for holding the rods in various extended positions, so as to hold the grate bars in various inclined positions, the free ends of the rods with the notches being provided with handles 45 for the manual manipulation thereof.

In testimony whereof I have affixed my signature.

EUGENIO FERNANDEZ.
